UNITED STATES PATENT OFFICE.

SALVATORE PALMIERI, OF ROCHESTER, NEW YORK.

METHOD OF MAKING SHOES AND HEEL-SECURING MEANS USED IN SUCH METHOD.

Application filed April 9, 1924. Serial No. 705,382.

The present invention relates to a method of making shoes and a heel securing means used in such method, this application being a continuation in part of an application filed by me on May 14th, 1923, Serial No. 638,787. An object of this invention is to provide for effectively securing a French or wooden heel to a shoe. Another object of the invention is to provide a heel securing means which may be attached directly to the inner sole before the upper is lasted, so that the securing means is firmly attached to the shoe.

To these and other ends, the invention consists of certain parts and combinations of parts, all of which will be hereinafter described; the novel features being pointed out in the appended claims.

In the drawings:

Fig. 1 is a fragmentary side view of a last showing a fragment of the inner sole secured thereto and the anchoring member of the heel securing means in position;

Fig. 2 is a plan view of a fragment of the under side of the inner sole;

Fig. 3 is a fragmentary plan view showing the underside of the shoe after the upper has been lasted to the inner sole;

Fig. 4 is a fragmentary plan view showing the underside of the shoe after the outer sole has been placed in position;

Fig. 5 is a fragmentary side view of the shoe showing the heel anchoring prongs in position;

Fig. 6 is a top view of the heel, showing the opening in the heel seat;

Fig. 7 is a fragmentary view of a shoe showing the heel in position and in longitudinal section; and

Fig. 8 is a perspective view of the securing means.

In the illustrated embodiment of the invention the last 1 has the inner sole 2 secured thereto in the usual manner. The anchoring plate 3 is then secured to the inner sole by tacks 4 or other suitable means. In this instance, the anchoring member embodies a sheet metal plate cut out at its center to provide three inwardly extending tongues 5, 6 and 7, the tongue 5 extending forwardly from the rear portion of the plate and the tongues 6 and 7 extending inwardly or toward each other from the side portions of the plate, and the plate as a whole being

tempered so that the tongues and the plate 55 are resilient. Each tongue is provided with an opening 8 which has screw threaded walls.

After the plate is secured to the inner sole, the upper 9 is lasted, the inwardly 60 turned portion of the upper covering the sides and rear portion of the plate as shown in Fig. 3, leaving the tongues 5, 6 and 7 exposed. Thereafter, the outer sole 9^a is secured in place, this outer sole not extending 65 over the heel portion so that the tongues 5, 6 and 7 may also be exposed. Three heel anchoring devices 10, 11 and 12 with inner screw threaded ends are now secured in the screw threaded openings of the tongues 5, 6 70 and 7 respectively. These heel anchoring devices are pointed and are provided with barbs 13 being formed preferably of the same material of which wire nails are formed so that they are pliable. The heel 75 14 is now attached. Before the heel is attached it is provided with three openings 15, 16 and 17. These openings are for the purpose of centering the anchoring nails 10, 11 and 12 but are not so deep as the 80 nails are long so that, when the heel is driven in place on the shoe, the nails will, after passing through the openings, pass into the material of the heel. The openings are arranged in diverging relation so that openings are spread or diverged with reference to each other. The nail 10 which is near the rear portion of the heel is shorter than the nails 11 and 12 so that it will not pass completely through the rear shallow projecting 90 portion of the heel.

From the foregoing it will be seen that there has been provided a new method of securing wooden or French heels to shoes. According to this method an anchoring 95 member is fastened to the inner sole before the upper is lasted so that this anchoring member lies between the inner sole and the inwardly turned portion of the upper. Spring tongues are provided on the anchoring member and carry anchoring prongs which enter into openings in the heel, the heel being applied after the lasting operation and operation of attaching the outer sole has been completed. The openings in 100 the heel spread the prongs so that an effective connection is provided between the heel and the shoe. The spring tongues provide

a resilient support for the prongs so that the prongs may be deflected sidewise to permit them to be entered into the openings of the heel.

5 When the anchoring prongs are pressed inwardly, they not only tend to deflect the tongues, but to twist the whole plate or anchoring member so that after the prongs have been driven home into the heel, this distortion of the plate acts to maintain the gap between the heel and the shoe proper in a closed condition.

10 What I claim as my invention and desire to secure by Letters Patent is:

15 1. In combination with a shoe, a member secured to the shoe in the heel portion thereof, prongs resiliently supported by said member, and a heel having diverging openings into which said prongs extend.

20 2. In combination with a shoe, tongues provided with screw threaded openings, prongs secured in said screw threaded openings, and a heel having diverging openings into which said prongs extend for securing

25 the heel to the shoe.

3. A shoe comprising an inner sole, an upper with inturned portions at its heel secured to the underside of the inner sole, a heel securing plate secured between the inner sole 30 and the inturned portions of the upper, said plate having tongues provided with screw threaded openings, pliable prongs secured in the screw threaded openings, and a heel having diverging openings in which said 35 prongs extend.

4. A shoe comprising an inner sole, an upper having inturned portions at its heel, heel securing means secured between the inner

sole and the inturned portion of the upper, and having also diverging prongs removably secured, and a heel having diverging openings through its seat in which said prongs extend.

5. In combination with a shoe, a resilient member secured to the heel portion thereof, prongs resiliently supported by said member, and a heel having diverging openings into which said prongs extend.

6. A method of making shoes which consists in attaching a resilient member to the underside of the inner sole, lasting the upper to cause the inturned portions thereof to cover portions of said member, attaching the outer sole, connecting heel anchoring prongs to the resilient member, providing a heel with diverging openings therein, deflecting said heel anchoring prongs to distort the resilient member and cause the prongs to enter said openings and forcing the prongs into the diverging openings of the heel, while the resilient member is under distortion.

7. A method of making shoes which consists in providing a shoe having a resilient member provided with diverging prongs and secured to the underside of the inner sole thereof with the inturned portions of the upper covering portions of said resilient member, providing a heel with diverging openings, deflecting the prongs on the resilient member to distort the member and to cause the prongs to enter the diverging openings of the heel, and forcing the prongs into said diverging openings.

SALVATORE PALMIERI.
